UNITED STATES PATENT OFFICE.

PAUL CANNELL AND WILLIAM D. CANNELL, OF WATERLOO, NEBRASKA.

APPARATUS FOR VENDING LIQUID.

1,176,649.

Specification of Letters Patent. Patented Mar. 21, 1916.

Application filed February 8, 1915. Serial No. 6,823.

To all whom it may concern:

Be it known that we, PAUL CANNELL and WILLIAM D. CANNELL, citizens of the United States, residing at Waterloo, in the county of Douglas and State of Nebraska, have invented certain new and useful Improvements in Apparatus for Vending Liquid; and we do hereby declare the following to be a full, clear, and exact description of the invention, such as will enable others skilled in the art to which it appertains to make and use the same.

The present invention relates to apparatus for vending liquids, and consists more particularly in an improved apparatus for vending such liquid as gasoline, designed to be placed at suitable intervals along highways for the convenience of motorists, and which will be inclosed to prevent tampering or operation by unauthorized persons prior to depositing a proper coin therein.

Our invention is designed to utilize the rack and pinion pumping mechanism, now usually employed to raise gasoline and other liquids from sunken wells or reservoirs; and the invention has for an object to provide an improved coin or check-controlled apparatus for normally locking the pumping mechanism to prevent unauthorized delivery of fluid, and which, on depositing a suitable coin, will release such mechanism and permit pumping of a quantity of gasoline proportional to the denomination of the coin.

Another object of the present invention resides in providing an improved apparatus of the above character including a novel mechanism for compelling full strokes of the pump whereby delivery of the proper amount of gasoline will be assured, at the same time rendering it impossible to operate the pump on short strokes without shifting the locking device into engagement therewith.

The invention has for a further object to provide means for limiting the strokes of the pump and for adjusting same to secure variable stroke lengths corresponding to the price per gallon of gasoline, which, as is well-known, has a fluctuating value.

With the foregoing and other objects in view the invention consists in the constructions, combinations and arrangements herein described and claimed.

In the accompanying drawings forming a part of this application, and in which similar reference symbols indicate corresponding parts in the several views: Figure 1 is a side elevational view of an apparatus constructed in accordance with the present invention. Fig. 2 is an end elevation of the same. Fig. 3 is an enlarged view of the full-stroke mechanism. Fig. 4 is a vertical sectional view of the coin-controlled apparatus, illustrating the pump pinion and rack in dotted lines. Fig. 5 is a transverse section view of the same and showing the pump elements in full lines. Fig. 6 is a top plan view, partly in section, of the coin-controlled apparatus; and Fig. 7 is an enlarged fragmentary perspective view of the same.

Referring more particularly to the drawings, and especially to Figs. 1 and 2 thereof, 1 designates a housing erected on the surface above a sunken well or tank 2, containing gasoline or other liquid to be vended; said housing 1 being constructed to inclose the several mechanisms of the apparatus and prevent fraudulent tampering therewith. In the tank 2 is located the usual pump cylinder 3, wherein reciprocates a valved or other plunger 4, connected to be operated by a piston rod 5 from a rack 6 in mesh with a pinion 7, the same being arranged to be actuated by a crank handle 8 projecting from the housing 1. From the cylinder 3 leads a pipe 9 to a delivery spout 10, from which the gasoline may be collected in buckets, or may be delivered directly through a hose to the fuel tank of a motor vehicle. The pumping mechanism is normally locked, to prevent unauthorized persons operating the same prior to depositing a coin in the machine, by a latch 11, under the control of a coin or check-control apparatus mounted in a casing 12 and secured to the housing 1 in any suitable manner. The coin-controlled apparatus is more particularly illustrated in Figs. 4 to 7, inclusive, and will be hereinafter referred to in detail.

To insure full strokes of the pump plunger a full-stroke mechanism is provided to engage the pinion 7, and mounted on a frame 13 within the housing 1. Such full-stroke mechanism is more particularly

shown in Fig. 3 to comprise a double acting pawl 14, pivoted on the frame 13 as indicated at 15, and formed at its opposite end with teeth 16 and 17 adapted to engage between the teeth of the pinion 7. The teeth 16 and 17 of the double acting pawl 14 are held to yieldingly engage the pinion 7 by a coil spring 18; and it will be understood that when the tooth 16 is in engagement with the pinion, the latter will be permitted to rotate in a clockwise direction only, as seen from Fig. 3; and while the tooth 17 is in engagement with the pinion, as shown in Fig. 1, the pinion 7 will be permitted to rotate in a counterclockwise direction and will be locked against rotation in the opposite direction. The double acting pawl 14 is provided with a rearwardly extending arm 19, coupled by a loose joint 20 to a link 21, the opposite end of which latter is connected to one arm of a bell crank lever 22 fulcrumed at one end of the frame 13, as indicated at 23. At the opposite end of the frame 13 is fulcrumed a similar bell crank lever 24, connected to actuate the bell crank 22 through a bent link 25. The horizontal arm of the bell crank lever 24 extends into the path of a projection 26, mounted on the lower end of the rack bar 6, and adapted to be engaged by the latter on the upward limit of movement of the rack bar to rock said bell crank lever, and through the associated links 25 and 21 and the bell crank 22, shift the tooth 17 of the double acting pawl 14 from the position shown in Fig. 1 to the position shown in Fig. 3, where the tooth 16 is in engagement with the pinion 7. The crank handle 8 is thereupon reversed and the pinion 7 rotated in a clockwise direction to move the rack 6 downwardly and disengage the projection 26 from the bell crank lever 24. At the lowermost limit of its travel, the projection 26 on the rack 6 is adapted to engage an arm 27, carried by the lower end of a rod 28 adjustably mounted in a scale bar 29, and held in position after adjustment by a set screw 30. The rod 28 is provided at its upper end with a pointer 31 arranged to travel over the scale 29, whereby the stroke of the rack 6 may be regulated in accordance with the prevailing market price of the liquid to be vendored. The scale bar 29 is suspended from a rod 32, supported from the horizontal arm 24 of the bell crank lever 24. As indicated in dotted lines in Fig. 3, it will be understood that when the rack 6 descends to the lowermost limit of its travel, the projection 26 encounters the arm 27 and moves the rod 28 and associated parts to rock the bell crank 24 and shift the tooth 17 into engagement with the pinion 7, as shown in Fig. 1; whereupon the said pinion may be reversed by the crank handle 8 and operate to raise the rack 6.

Referring more particularly to Figs. 4 to 7, inclusive, the apparatus for controlling the operation of the latch 11 is contained within a casing 12, as above stated; the said casing 12 being divided by a partition 33 into two transverse vertical compartments 34 and 35, the former of which is formed with a depressed bottom 36 providing a depository for the coins. The latch 11 is slidably mounted in a guide 37, secured to the housing 1, and is provided with a finger 38 projecting through a slot 39 formed in the wall of the casing 12 adjacent the housing 1, and resting on the outer free end of an arm 40 fixedly mounted on a rock shaft 41. The arm 40 is normally in the raised position shown in full lines in Figs. 4 and 5, where it maintains the latch 11 in engagement with the pinion 7 and effectually blocks the pumping mechanism. On the rock shaft 41 are mounted a plurality of short arms 42, 43 and 44, formed each with a slot 45 into which projects a key 46 on the rock shaft; and whereby the short arms 42, 43 and 44 may be actuated individually to impart movement to the rock shaft 41 without affecting the position of the companion arms. The outer ends of the short arms 42, 43 and 44 are preferably bifurcated, as shown in Figs. 5 and 7, for receiving the lower ends of toggle levers 47, 48 and 49, suspended from a rod 50 mounted transversely in the walls of the compartment 35. The upper members of the toggle levers, as illustrated to advantage in Fig. 4, are adapted to normally occupy a position in close contact with the partition 33, and are actuated by the coin carrier, as hereinafter described, to move into the dotted line position shown in this figure and depress the corresponding short arms 42, 43 and 44 to rock the shaft 41 and shift the arm 40 to the lower position permitting the latch 11 to drop by gravity and disengage the pinion 7. Each of the upper members of the toggle levers 47, 48 and 49 is provided with projections 51 adapted to be engaged by notches 52 provided in latch bars 53, 54 and 55, mounted to swing on a rod 56 and supported at their outer ends upon said projections 51. The complementary projections 51 and notches 52 in the several latch bars 53, 54 and 55 operate to maintain the respective toggle levers 47, 48 and 49 in operated position until lifted, by a carriage 57 to disengage the projections and notches and permit the levers to be returned to initial position by springs 58 engaged beneath the short arms 42, 43 and 44. The carriage 57 is mounted to slide transversely of the compartment 35 on a plurality of rods 59 arranged preferably in triangular formation, and the same is returned to initial position to the left of the compartment by a coil spring or other suitable device 60. A cam piece 61 is mounted on the carriage 57 to one

side of the upper supporting rod 59 for engaging the under sides of the latch bars 53, 54 and 55 for raising the same to disengage the notches 52 thereof with the projections 51 on the several toggle levers. On the opposite side of the upper supporting bar 59 the carriage 57 is formed with a rack 62, adapted to be engaged by a pawl 63 pivoted as indicated at 64 in the compartment 35 of the casing 12 and provided with a pin 65 in proximity to its outer free end for engagement by an L-shaped member 66, the same being connected to the arm 40 as indicated at 67 in Fig. 4. The underside of the carriage 15 57 projects beneath the lower supporting bars 59, and is similarly provided with a rack 68 engaged by a weighted pawl 69 pivoted on a bell crank lever 70 mounted in brackets 71, and having its horizontal arm projecting 20 through a slot in the casing wall to be engaged by a lug 72 mounted on the rack 6, and formed with an offset portion 73 for receiving the arm 40. The weighted pawl 69 is, at its butt end, provided with a pin 74 engaging through a slot 75 formed in the lower end of a link 76, pivoted at its upper end in the horizontal extension of the L-shaped lever 66. In the compartment 34 of the casing 12 is journaled a shaft 77 on which are 30 mounted a plurality of angular levers 78, supporting at their upper ends a coin carrier 79. The coin carrier 79 is provided with a plurality of compartments, slotted at their upper ends, as indicated at 80, 81 and 82, of 35 different dimensions to accommodate coins of various denominations. In the initial position of the coin carrier 79 as shown in full lines in Figs. 4 and 7, the coins are prevented from dropping through the compartments 40 therein by means of a bottom 83 secured to the front wall of the casing 12, as indicated at 84. The front and rear walls of the coin carrier are preferably inclined, as illustrated to advantage in Fig. 4, and each compartment 45 thereof is provided with a fraud-preventing device 85, for removing washers; and it is to be understood that any other well known fraud-preventing device may be employed in conjunction with the present apparatus. The front walls of each of the coin compartments 80, 81 and 82 of the coin carrier 79 are constructed with swinging gates 86, 87 and 88, respectively, provided each with pins or projections 89, 90 and 91. 50 The coin carrier 79 is exposed, for the insertion of coins, through an opening 92, in the top of the casing 12, as will be seen from an inspection of Fig. 6, and may be operated by a hand-grasp 93 projecting above the casing, as illustrated, and operating in a slot 94 formed therein. Subsequent to the insertion of the proper coin, the carrier 79 is adapted, through the hand-grasp 93, to be oscillated on the supporting levers 78 to the dotted line 55 position shown in Fig. 4, when the projections 89, 90 and 91 will enter perforations 95 provided in the partition 33, and operate to force the respective toggle levers 47, 48 and 49 into the dotted line position therein shown. Where the coin carrier 79 is thus 60 oscillated without previously inserting a coin therein, the gates 86, 87 and 88 will be moved inwardly within the compartments 80, 81 and 82, respectively, when the pins 89, 90 and 91 encounter the respective toggle levers 47, 48 and 49, and will be ineffectual to actuate the latter. Upon the deposition of a coin in one of the compartments of the carrier 79, the corresponding swinging gate will be prevented thereby from inward 65 movement, and will consequently actuate the corresponding toggle lever when the coin carrier is swung into actuating position. In the casing 12, above the coin carrier 79, is journaled a shaft 96 whereon are mounted a plurality of levers 97, one for each compartment of the coin carrier 79, and provided with downwardly extending arms 98 in the path of the coin carrier and adapted to be engaged thereby to revolve the levers to 70 force the coins through the bottoms of the compartments, as indicated in dotted lines in Fig. 4.

The machine is adapted to contain a notice of the prevailing market price of the gasoline per gallon, and to this end the top of the casing 12 is provided with an inspection opening 99, to the immediate right of which is placed a cent mark, indicated at 100. Within the casing 12 is arranged a number wheel 101, to which access may be had by the proprietor of the machine for revolving the same to bring the proper number thereon in registry with the inspection opening 99 and opposite the cent mark 100 to notify purchasers of the prevailing price of the gasoline, and for which the pumping mechanism has been set to correspond.

In operation a quarter, half dollar or dollar is inserted in the corresponding slot 80, 81 or 82 of the coin carrier 79, the same assuming the position in the respective coin compartment, as indicated in dotted lines in Fig. 4; and it is to be understood that although, for convenience of illustration, we have shown the coin box 79 as comprising but three separate compartments, the same may be constructed of any suitable number and the associated parts of the apparatus multiplied accordingly. When, for instance, a quarter is inserted in the slot 80 of the coin carrier 79, the same takes up a position between the rear wall of the coin compartment and the swinging gate 86 thereof, preventing the latter from moving into the compartment when the coin carrier is pushed rearwardly by the hand-grasp 93. When the purchaser so operates the coin carrier, the pin 89 on the swinging gate 86 of the compartment 80 will enter its perforation 110 115 120 125 130

ration 95 in the partition 33, and actuate the respective toggle lever 47 to move into the dotted line position indicated in Fig. 4. In this position the projection 51 on the toggle lever 47 will be moved into registry with the notch 52 in the latch bar 53, which will drop by gravity, and maintain the toggle lever 47 in such position until lifted by the cam piece 61 on the carriage 57. Meanwhile the pins 90 and 91 on the swinging gates 87 and 88, respectively, will not be effectual to actuate their corresponding toggle levers 48 and 49, but will swing forwardly within the coin carrier 79 when said pins encounter the levers. The toggle lever 47, so actuated, will depress the associated short arm 42, which will engage the key 46 and rock the shaft 41 to shift the arm 40 to the dotted line position shown in Fig. 4, whereupon the latch 11 will be released and permitted to fall by gravity to disengage the pinion 7 of the pump mechanism. During such action the companion short arms 43 and 44 will remain unaffected and in initial position the key 46 on the shaft 41 traveling in the slots 45 formed therein. When the arm 40 descends the L-shaped member 66 will be drawn down and permit the pawl 63 to engage the rack 62 formed on the upper surface of the carriage 57. The pumping mechanism will now be free to be operated through the crank handle 8, and as shown, the arrangement will allow two full strokes of the pump plunger 4 before the latch 11 will be again moved to engage and lock the pinion 7. During each upward movement of the rack 6 the lug 72 will engage the outer projecting end of the bell crank lever 70 and rock the same about the pivotal connection provided by the bracket 71. Such rocking movement is transmitted to the weighted pawl 69 to advance the carriage 57 through a distance corresponding to one tooth on the lower rack 68. Upon the descent of the rack 6 the lug 72 will disengage the bell crank lever 70, which will fall by gravity into the position shown in full lines in Fig. 5, and operate to retract the weighted pawl 69 to engage the next rearward notch in the rack 68 in readiness for the next actuation. After two complete strokes of the rack 6 have been made, the cam piece 61 will have advanced and raised the latch bar 53 to disengage the notch 52 therein from the projection 51 on the toggle lever 47. The toggle lever 47 will thereupon be released to the influence of the spring 58 which will restore the short arm 42 to initial position and return the toggle lever to engagement with the partition 33. The arm 40 will similarly be raised and lift the latch 11 through the finger 38, into engagement with the pinion 7 and again lock the pumping mechanism. It will be understood that if a half dollar is inserted in the slot 81, the corresponding pin

90 will actuate the toggle lever 48, which will be held in position by means of the latch bar 54 until the cam piece 61 on the carriage 57 raises the same to disengage the associated notch 52 and projection 51. The latch bar 51 is located a distance from the initial position of the cam piece 61 corresponding substantially to twice the distance of the latch bar 53 therefrom, and consequently four strokes of the pumping mechanism will be permitted before said cam piece advances beneath the latch bar 54. Similarly, when one dollar is inserted in the compartment 82 of the coin carrier 79, the corresponding toggle lever 49 will be actuated and held in position by the latch bar 55 situated from the cam piece twice the distance of the adjacent latch bar 54, and consequently will permit eight strokes of the pumping mechanism before the latter is again blocked. Upon the return of the arm 40 to raised position after each actuation, the L-shaped member 66 will be lifted and raise the pawl 63 through the pin 65 to disengage the upper rack 62, and rock the weighted pawl 69 by means of the link 76 to disengage the lower rack 68 and permit the spring 60 to return the carriage 57 to initial position at the left of the casing 12, as seen in Fig. 5.

It will be understood that the proprietor of the apparatus will have access to the interior of the housing 1, for adjusting the rod 28 over the scale 29 to increase or decrease the distance between the same and the horizontal arm of the bell crank lever 24, as to thereby alter the stroke lengths of the rack 6 in accordance with the variation in price of the gasoline. This variation, as above described, will be ascertained by the purchaser from the number on the wheel 101 appearing through the inspection opening 99 in the top of the casing 12.

It is obvious that those skilled in the art may vary the details of construction and arrangements of parts without departing from the spirit of our invention, and therefore we do not wish to be limited to such features except as may be required by the claims.

We claim:

1. In an apparatus for vending liquid, the combination of a rack, a pinion engaging said rack, a latch normally in engagement with said pinion, a coin-receiving mechanism for controlling said latch to release the pinion, a pair of oppositely-acting pawls arranged to engage said pinion alternately, a plurality of movable stops for limiting the stroke of said rack in either direction and adapted to be actuated thereby, connections between one of said stops and said pawls for shifting the latter at the completion of each rack stroke, an adjustable coupling connecting said stops for varying the distance therebetween to pro-

- vide different stroke lengths for the rack, and a scale interposed in said coupling for facilitating adjustment thereof, substantially as described.
- 5 2. In an apparatus for vending liquid, the combination of a rack, a pinion engaging said rack, a latch normally in engagement with said pinion, a coin-receiving mechanism for controlling said latch to release the pinion, a pair of oppositely-acting pawls arranged to engage said pinion alternately, a plurality of movable stops for limiting the stroke of said rack in either direction and adapted to be actuated thereby, 10 connections between one of said stops and said pawls for shifting the latter at the completion of each rack stroke, a two-part coupling connecting said stops, a scale carried by one of said coupling members and 15 adjustably engaging said other member, and a pointer on said latter member operating over said scale for indicating the required adjustment, substantially as described.
- 20 3. In an apparatus for vending liquid, the combination of a rack, a pinion engaging said rack, a latch normally in engagement with said pinion, a coin-receiving mechanism for controlling said latch to release the pinion, a pair of oppositely-acting pawls arranged to engage said pinion alternately, a lever, a stop adjustably supported from said lever, link connections between 25 said lever and pawls, and a projection on said rack for encountering said lever and stop to rock the former and shift said pawls at the completion of the upward and downward strokes, respectively, substantially as described.
- 30 4. In an apparatus for vending liquid, the combination of a rack, a pinion engaging said rack, a latch normally in engagement with said pinion, a coin-receiving mechanism for controlling said latch to release the pinion, a pair of oppositely-acting pawls arranged to engage said pinion alternately, a lever, a stop, a divided connection for suspending said stop from the lever, a scale interposed in said connection, means 35 for adjusting the members of said divided connection over said scale, connections between said lever and pawls, and a projection on said rack for encountering said lever and stop to rock the former and shift said pawls at the completion of the upward and downward strokes, respectively, substantially as described.
- 40 5. In an apparatus for vending liquid, the combination of a movable device, a latch, a rock shaft, means mounted on said rock shaft and normally maintaining the latch in engagement with said movable device, a plurality of independent connections for operating said rock shaft, a coin carrier provided with a plurality of compartments for receiving coins of various denominations, and means associated with each of said compartments for actuating the associated connections only when coins are deposited therein, substantially as described.
- 45 6. In an apparatus for vending liquid, the combination of a movable device, a latch, a rock shaft, means mounted on said rock shaft for normally maintaining said latch in engagement with the movable device, a plurality of independent connections for operating said rock shaft, a coin carrier, coin-controlled means mounted on said coin carrier for selectively actuating said connections, and means for retaining said connections in operated position, substantially as described.
- 50 7. In an apparatus for vending liquid, the combination of a movable device, a latch, a rock shaft, means mounted on said rock shaft and normally maintaining said latch in engagement with the movable device, a plurality of independent connections for operating said rock shaft, a coin carrier, coin-controlled means mounted on said coin carrier for selectively actuating said connections, means for retaining said connections in operated position, and means for releasing said connections, substantially as described.
- 55 8. In an apparatus for vending liquid, the combination of a movable device, a latch, a rock shaft, means mounted on said rock shaft for normally maintaining said latch in engagement with the movable device, a plurality of individual connections for said rock shaft, coin carrier, coin-controlled means mounted on said coin carrier for selectively actuating said connections, latch bars for retaining said connections in operated position, and a carriage mounted for movement beneath said latch bars and adapted to lift the same in succession to disengage said connections, substantially as described.
- 60 9. In an apparatus for vending liquid, the combination of a movable device, a latch, a rock shaft, means mounted on said rock shaft for normally maintaining said latch in engagement with the movable device, a plurality of individual connections for said rock shaft, a coin carrier, coin-controlled means mounted on said coin carrier for selectively actuating said connections, latch bars for retaining said connections in operated position, a carriage mounted for movement beneath said latch bars and adapted to lift the same in succession to disengage said connections, and means for advancing said carriage, substantially as described.
- 65 10. In an apparatus for vending liquid, the combination of a movable device, a latch, a rock shaft, means mounted on said rock shaft for normally maintaining said latch in engagement with the movable device, a

- 6
- plurality of individual connections for said rock shaft, a coin carrier, coin-controlled means mounted on said coin carrier for selectively actuating said connections, latch bars for retaining said connections in operated position, a carriage mounted for movement beneath said latch bars and adapted to lift the same in succession to disengage said connections, means associated with said movable device for advancing said carriage, and means for returning said carriage to initial position, substantially as described.
11. In an apparatus for vending liquid, the combination of a movable device, a latch, means for normally maintaining said latch in engagement with the movable device, a plurality of toggle levers for moving said means to release the latch, a coin carrier, and coin-controlled means carried by said coin carrier for selectively actuating said toggle levers, substantially as described.
12. In an apparatus for vending liquid, the combination of a movable device, a latch, means for normally maintaining said latch in engagement with the movable device, a plurality of independently movable toggle levers connected each to said means for moving the latter to release the latch, a movable coin carrier, and coin-controlled means mounted on said coin carrier for engaging and actuating each of said toggle levers independently, substantially as described.
13. In an apparatus for vending liquid, the combination of a movable device, a latch, means for normally maintaining said latch in engagement with said movable device, a plurality of levers associated with said means and arranged to move the latter to release said latch, a movable coin carrier and a coin-controlled projection on said coin carrier for each of said levers and arranged to actuate the latter selectively when the coin carrier is moved, substantially as described.
14. In an apparatus for vending liquid, the combination of a movable device, a latch, means for normally maintaining said latch in engagement with said movable device, a plurality of levers associated with said means and adapted to move the same to release said latch, a movable coin carrier, a coin-controlled projection on said coin carrier for each of said levers and arranged to actuate the latter when the coin carrier is moved, a latch bar for each of said levers whereby to maintain the same in operated position, and means for lifting said latch bars in succession to release said levers, substantially as described.
15. In an apparatus for vending liquid, the combination of a movable device, a latch, a rock shaft, means mounted on said rock shaft for normally maintaining said latch in engagement with said movable device, a plurality of toggle levers connected to operate said rock shaft, a movable coin carrier, a plurality of coin-controlled projections on said coin carrier, one for actuating each of said toggle levers, an independent latch bar for retaining each of said toggle levers in operated position, a carriage for lifting each of said latch bars in succession, means for advancing said carriage, and means for returning said carriage to initial position, substantially as described.
16. In an apparatus for vending liquid, the combination of a movable device, a latch, means for normally maintaining said latch in engagement with said movable device, individually operable mechanisms for controlling the movement of said means, a coin carrier divided to provide compartments corresponding in number to the number of said mechanisms and for receiving coins of various denominations, movable gates associated one with each of said compartments and adapted to be held against inward movement by the coins, and means carried by said movable gates for engaging said mechanisms for shifting said means to release said latch, substantially as described.
17. In an apparatus for vending liquid, the combination of a movable device, a latch, means for normally maintaining said latch in engagement with said movable device, a plurality of individually operable mechanisms for controlling the movement of said means, a movable coin carrier providing a plurality of compartments for receiving coins of different denominations, a swinging gate for each of the compartments in said coin carrier and adapted to be held against inward movement by the coins, projections on each of said gates arranged to engage and actuate the respective mechanisms for controlling the movement of said means to release the latch and means for moving said coin carrier, substantially as described.
18. In an apparatus for vending liquid, the combination of a movable device, a latch, means for normally maintaining said latch in engagement with said movable device, a plurality of mechanisms for controlling the operation of said means, coin-controlled means for independently operating said mechanisms, latch means for retaining said mechanisms in operated position, a carriage adapted to advance and lift said latch means successively out of engagement with the respective mechanisms, means for advancing said carriage from said movable device, and means for returning said carriage to initial position after each advance actuation, substantially as described.
19. In an apparatus for vending liquid, the combination of a movable device, a latch, means for normally maintaining said latch in engagement with said movable device, a plurality of mechanisms for controlling the

- operation of said means, coin-controlled means for independently operating said mechanisms, latch means for maintaining said mechanisms in operated position, a carriage, means for advancing said carriage to engage and release said latch means successively from engagement with said mechanisms, pawl and ratchet elements for advancing said carriage, connections for operating said pawl and ratchet elements from the movable device, means for disengaging said pawl and ratchet connections upon completion of the advance movement of said carriage, and means for returning said carriage to initial position after said pawl and ratchet elements have been disengaged, substantially as described.
20. In an apparatus for vending liquid, the combination of a movable device, a latch, 20 means for normally maintaining said latch in engagement with said movable device, a plurality of mechanisms for independently operating said means, a coin-controlled device for individually operating said mechanisms, latch means for maintaining said mechanisms in operated position, a carriage for raising said latch means from engagement with said mechanisms, a rack on said carriage, a movable pawl for engagement 25 with said rack to advance the carriage step by step, means for actuating said pawl, a second pawl for maintaining said carriage in position during the return of said movable pawl, means for moving said pawls to 30 disengage the carriage upon completion of the advance movement of the same, and means for returning said carriage to initial position after each actuation, substantially as described.
40. 21. In an apparatus for vending liquid, the combination of a movable device, a latch, means for normally maintaining said latch in engagement with said movable device, mechanism for controlling the movement of 45 said means, a coin-controlled device for operating said mechanism, latch means for retaining said mechanism in operated position, a carriage for lifting said latch means to disengage said mechanism, a rack on said 50 carriage, a movable pawl for engaging said rack to advance the carriage step by step, means for actuating said pawl, a second pawl engaging with said carriage to prevent return while said movable pawl is 55 stored to initial position, a connection between said pawls, means arranged between one of said pawls and said first-named means for moving the same to disengage the carriage upon completion of the advance movement, and means for restoring said carriage to initial position after each actuation, substantially as described.
22. In an apparatus for vending liquid, the combination of a movable device, a 60 latch, means for normally maintaining said latch in engagement with said movable device, a coin-controlled device for operating said mechanism, latch means for retaining said mechanism in operated position, a carriage for lifting said latch means to disengage said mechanism, a rack on said carriage, a movable pawl for engaging said rack to advance the carriage step by step, means for actuating said pawl, a second pawl engaging with said carriage to prevent return while said movable pawl is stored to initial position, a connection between said pawls, means arranged between one of said pawls and said first-named means for moving the same to disengage the carriage upon completion of the advance movement, and means for restoring said carriage to initial position after each actuation, substantially as described.
23. In an apparatus for vending liquid, the combination of a movable device, a latch, means for normally maintaining said latch in engagement with said movable device, a plurality of toggle levers for controlling the movement of said means, coin-controlled means for independently operating each of said toggle levers, a latch bar 85 for retaining each of said toggle levers in operated position, a carriage mounted to move transversely of said latch bars, means on said carriage for engaging and lifting said latch bars to disengage toggle levers, means for advancing said carriage, and means for returning said carriage to initial position, substantially as described.
24. In an apparatus for vending liquid, the combination of a movable device, a latch, means for normally maintaining said latch in engagement with said movable device, a plurality of independently movable levers for controlling the operation of said means, a coin carrier mounted to swing into engagement with said levers and divided into compartments for receiving coins of different denominations, movable projections on said coins carrier under the control of the coins and adapted to engage and operate said levers, latch bars for retaining said levers in operated position, a transversely movable carriage arranged to disengage said latch bars in succession from said levers, means for advancing said carriage, and means for returning said carriage to initial position after each actuation, substantially as described.
25. In an apparatus for vending liquid, the combination of a movable device, a latch, means for normally maintaining said latch in engagement with said movable device, a plurality of individually operable mechanisms for controlling said means, a coin carrier mounted to swing into engagement with said mechanisms, compartments in said coin carrier for receiving coins of different denominations, movable projections under the control of the coins for each of said compartments adapted to engage and operate the several mechanisms, a latch bar for each of said mechanisms, a carriage mounted to move transversely of and release said latch bars in succession, pawl and rack elements for advancing said carriage, 120

means for actuating said elements, and means for restoring the carriage to initial position after each actuation, substantially as described.

26. In an apparatus for vending liquid, the combination of a movable device, a latch, a rock shaft, an arm on said rock shaft in engagement to normally maintain said latch blocking said movable device, a plurality of independently movable levers mounted on said rock shaft, a coin carrier mounted to swing into engagement with said levers, compartments in said coin carrier for receiving coins of various denominations, movable projections under the control of the coins for each of said compartments adapted to engage and operate said levers, latch bars for retaining said levers in operated position, a carriage for lifting said latch bars in succession from engagement with said levers, means for restoring said levers to initial position, means for advancing said carriage, and means for retracting said carriage after each advance actuation, substantially as described.

27. In an apparatus for vending liquid, the combination of a rack, a pinion engaging said rack, a latch, means for normally maintaining said latch in engagement with said pinion, a plurality of independently movable mechanisms for controlling the operation of said means, a coin-controlled device for operating said mechanisms selectively, latch means for retaining each of said mechanisms in operated position, means for moving said latch means to disengage said mechanisms, means for returning said mechanisms to initial position and restoring said latch into engagement with said pinion, a double-acting pawl arranged to engage said pinion alternately, a lever, a stop adjustably supported from said lever, link connections between said lever and pawl, and a projection on said rack for encountering said lever and stop to rock the former and shift said pawls at the completion of the upward and downward strokes respectively, substantially as described.

28. In an apparatus for vending liquid, the combination of a rack, a pinion engaging said rack, a latch, means for normally maintaining said latch in engagement with said pinion, a plurality of mechanisms for controlling the operation of said means, a coin-controlled means for selectively operating said mechanisms, latch means for retaining said mechanisms in operated position, a carriage for moving said latch means to disengage said mechanisms, means for actuating said carriage, a pair of oppositely acting pawls arranged to engage said pinion alternately, an arm connected to shift said pawls, a stop suspended from said arm, and a projection on said rack for encountering said arm and stop to rock the former and

shift said pawls at the completion of the upward and downward strokes respectively, substantially as described.

29. In an apparatus for vending liquid, the combination of a rack, a pinion engaging said rack, a latch, means for normally maintaining said latch in engagement with said pinion, a plurality of levers connected to individually operate said means, coin-controlled means for actuating said levers, a latch bar for retaining each of said levers in operated position, a transversely movable carriage arranged to move said latch bars to disengage said levers, means for restoring said levers to initial position, means for advancing said carriage from the rack, means for returning said carriage to initial position after each actuation, a pair of oppositely acting pawls arranged to engage said pinion alternately, a lever, a stop, a divided connection for suspending said stop from said lever, a scale interposed in said connection, means for adjusting the members of said divided connection over said scale, connections between said lever and pawls, and a projection on said rack for encountering said lever and stop to rock the former and shift said pawls at the completion of the upward and downward strokes respectively, substantially as described.

30. In an apparatus for vending liquid, the combination of a rack, a pinion meshing with said rack, a latch normally in engagement to block rotation of said pinion, an arm associated with said latch and adapted to normally hold the same in engagement with said pinion, a rock shaft connected to actuate said arm to release the latch, a plurality of independently operating toggle levers mounted on said rock shaft and connected to separately oscillate the same, a coin carrier mounted to swing into engagement with said several toggle levers and divided to provide a plurality of compartments for receiving coins of various denominations, a movable gate for each of said compartments, projections on said movable gates for encountering and operating said toggle levers selectively, means for automatically restoring said toggle levers to initial position after each actuation, a latch bar for holding said toggle levers in operated position against the influence of said last-named means, a carriage mounted to move transversely of said latch bars, means on said carriage for encountering said latch bars and lifting the same in succession to disengage the associated toggle levers, means for advancing said carriage step by step, means for returning the carriage to initial position after each advance movement thereof, a pair of oppositely-acting pawls alternately engaging said pinion, a lever, connections between said lever and pawls for actuating the latter, a stop suspended from said lever,

an adjustable coupling connecting said stop and lever for varying the distance therebetween, a scale interposed in said coupling for facilitating adjustment, and a projection on said rack for alternately encountering said lever and stop for rocking the former in opposite directions to shift said pawls into and out of engagement with said pinion, substantially as described.

In testimony whereof, we affix our signatures, in presence of witnesses.

PAUL CANNELL.
